BATTERY FEED FOR TELEPHONE LINES
ACCESSIBLE TO CONNECTORS

Kurt Laas, Munich, Germany, assignor to Siemens & Halske Aktiengesellschaft Berlin and Munich, a corporation of Germany

Filed Mar. 6, 1959, Ser. No. 797,812

Claims priority, application Germany Mar. 10, 1958
7 Claims. (Cl. 179—18)

This invention relates to a circuit arrangement for providing battery feed for subscribers' lines accessible to connectors, in communication systems and particularly telephone systems.

The circuit arrangement according to the invention provides means for testing a line accessible to a connector, to ascertain whether the line is idle or busy. The switching means for the testing of a line reached by a connector, such as testing relays, are disposed in the connector in accordance with known technique; after the connector has been set by current impulse series transmitted from a calling party, with its wipers in engagement with the bank contacts of a desired called line, the testing circuit is closed for a predetermined testing interval. If the testing relay fails to operate within this testing interval, busy tone will be transmitted to the calling subscriber so as to cause him to replace the receiver, whereupon the connection is released.

These testing switching means are utilized only during the extension of calls, and since they are provided in each connector, their number is very great. The object of the invention is to reduce the number of testing switching means required and at the same time to simplify the connector. This object is realized by the invention by the provision of a battery feed transmission disposed ahead of the connector and containing switching means for the testing and for the connection of battery feed current to the called line, such battery fed transmission being seized by the connector after the setting thereof, by as seizure criterion rearwardly transmitted thereto.

The invention thus effects seizure of the test relay set and, accordingly, switching-in of the test switching means, only after the connector has been set to the desired called line, whereupon such line is tested for its idle or busy condition. Therefore, no particular criteria are during the extension of a call required for switching in such relay set which will be referred to as feed transmission. Wrong connections cannot result since the impulse conductor is in normal position of the feed transmission directly connected through, thus preventing mutilation of current impulse series during the seizure of the feed transmission. The arrangement of the feed transmission according to the invention is not only applicable in the case of telephone systems provided with centrally disposed setting sets, as shown in the illustrated example, but may be equally advantageously used in connection with telephone systems in which the switches for extending calls are controlled by impulse series directly transmitted from calling subscriber stations.

The various objects and features of the invention will appear in the course of the description which is rendered below with reference to the accompanying drawings showing an embodiment of a telephone system having switches which are set by setting sets respectively common to a plurality of switches. In the drawings,

FIGS. 1a and 1b show a storing device incorporated in such a system and arranged in the feed transmission for the calling subscriber;

FIGS. 2a and 2b show the feed transmission 3SpUe comprising the test switching means for the called line reached by a connector;

2

FIGS. 3a and 3b illustrate the connector and a setting set which is common to a plurality of connectors; and

FIG. 4 is an overall circuit representation of the telephone system serving as an example.

FIG. 4 will be discussed first so as to explain the operation of the telephone selection system, details of which are shown in the remaining FIGS. 1a to 3b.

The individual subscriber stations, such as, for example, station TN1 are connected to bank contacts of

10 a call finder VW which is directly connected with a feed transmission SpUe. As soon as a subscriber removes his receiver, a call finder starts to operate and establishes connection with such subscriber to extend the calling line to the feed transmission. The current impulse series transmitted by the calling subscriber by impulsewise interruption of the line loop cause impulsewise actuation of the line relay 1A which transmits the impulses to the storers Sp arranged in the feed transmission. Upon receipt of the first impulse, voltage is placed on the

20 outgoing conductor a102, causing energization of the start relay 2AN in the setting set ES which is common to a plurality of group selectors GW, such start relay 2AN starting operation of the connecting switch of the setting set, the connecting switch establishing connection with

25 the group selector which is connected together with the feed transmission. When the connecting switch reaches this group selector, the test relay 2Pa will be energized, thereby effecting restoration of the high resistance start relay 2AN. The current flowing over the conductor

30 a102 is at the same time increased, thereby causing energization of relay 1U which is disposed in the feed transmission and which is operative to initiate the transmission of the current impulses stored in the storers Sp. Responsive to each current impulse, voltage is disconnected from the a102-conductor, thereby causing restoration of the testing relay 2Pa in the setting set of the group selector.

35 The impulsewise operation of the testing relay effects impulsewise switching of a relay chain for marking the decade in accordance with the corresponding impulse series. As soon as the first current impulse series is transmitted from the storers, the group selector is actuated and sets its wipers in engagement with an idle contact of the designated decade. When this contact

40 is reached, the testing relay 2Pb is energized, stopping further motion of the group selector wipers and initiating disconnection of the setting set. As soon as the setting set is disconnected, ground is disconnected from the a102-conductor, thereby causing restoration of relay 1U in the feed transmission. During the delayed release of

45 the relay 1Y, shown in FIG. 1b, a test is made to ascertain whether the connection is to be extended to another exchange, requiring transmission over the a-conductor of current impulse series in the form of ground impulses, or is to remain in the same exchange. If the latter

50 is the case, no particular switching operations are effected and after restoration of the relay 1Y (FIG. 1b), voltage is again connected by way of relay 1U to the a102-conductor, so as to effect energization of the start relay 4AN of the setting set 4ES (FIG. 4), which is common

55 to a plurality of connectors. Thereupon, as soon as the connecting switch of the setting set 4ES has reached the connector 4LW, relay 1U is again energized and the next following current impulse series will be released.

60 However, if the call is to be extended to another exchange to which the current impulses are to be transmitted over the a-conductor in the form of ground impulses, voltage is connected by such other exchange, to the conductor a102 and relay 1D in the feed transmission

65 is energized. Switching operations are thereby effected in the feed transmission, as will be presently described more in detail with reference to FIGS. 1a and 1b, so as

to transmit the successive current impulses as ground impulses over the a -conductor.

After the current impulse series, which designates the decade in the connector, has been received in the setting set 4ES, switch-over relay 3U in the feed transmission 3SpUe and switch-over relay 4Ua in the setting set 4ES of the connector will be energized by way of the conductor $d203$. Relay 3U in the feed transmission completes a holding circuit for itself opening at the same time the energizing circuit. Relay 4Ua in the setting set of the connector will also be held in a holding circuit completed thereby. The energization of relay 3U in the feed transmission serves at the same time as a signal for releasing the connector for the decade selection. Relay 3U also actuates contact 3u for preparing a circuit for the energization of the seizure relay 3C. However, seizure relay 3C cannot energize at this time for lack of potential on the conductor $d203$ in the setting set of the connector.

When the connector has reached the designated decade, the testing relay 4P will be energized and disconnection of the ground potential in the setting set of the connector will be initiated. Relay 1U in the feed transmission 3SpUe and the connector LW. The line conductors and release of relay 1Y (FIG. 1b). Upon release of relay 1Y, voltage is by way of relay 1U again placed on conductor $a102$, signifying that the setting set of the connector is needed again. The setting set of the connector had been released responsive to energization of the testing relay 4P. When the connector reaches the marked step of the selected decade, the testing relay 4P will again energize and stop further operation of the connector. Depending upon the energization of the testing relay 4P, the seizure relay 3C of the feed transmission 3SpUe will be caused to energize. The seizure relay 3C now connects the testing circuit for the testing of the called subscriber's line. Moreover, if the called line is idle, ringing current will be placed on the line conductors extending to the called line. The calling subscriber receives at the same time the ringing tone. However, if the called line is busy, busy tone will be transmitted to the calling subscriber as a signal that he should replace the receiver, whereupon the connection is released.

As indicated in FIG. 4 in dotted lines, a further group selector, for example, in larger exchanges, a fourth group selector, may be disposed between the feed transmission 3SpUe and the connector LW. The line conductors and the control or private conductors of such group selector are directly connected through and the switching operations accordingly correspond to those already described.

FIGS. 1a and 1b show the supply transmission for the calling subscriber and the storage device for storing the train of pulses sent out by the subscriber. The storage device has laminations which are arranged in a circle and are pushed below a guide ring by a marker magnet corresponding to the number of pulses of a number. In each case, the last lamination remains standing above said guide ring and thus characterizes the end of a train of pulses. If for instance a train of pulses consists of seven impulses, the laminations 1 to 6 are pressed below the guide ring and the lamination 7 remains standing above the guide ring. Upon the feeding out of a series of pulses from this storing device, a switch arm 1pk55 is moved forward stepwise and upon coming against a lamination which is above the guide ring, closes a circuit for a relay which thereby characterizes the end of a train of pulses. Furthermore, the storage device also has normal-position contacts (off-normal contacts) $so67$ and $so75$, which are actuated on departure from normal position. The contact 1pe96 is opened when the end position is reached, that is, when the storage device is completely filled and interrupts the further receipt of the arriving current impulses.

The storage transmission shown in FIGS. 1a and 1b is

seized by the preceding connecting device, a call-finder, via the private conductor $c3$ as follows:

(1) +, . . ., $c3$ -wire, 1a22, 1v27, 1AUI, 1u28, 1k29, 1c32, —

In this circuit, the relay 1A is attracted and by opening its contact 1a22 opens the short circuit for the seizure relay 1C which is thereby inserted in the circuit (1) and energizes. Furthermore, the winding V of the transformer 1Ue is connected via contact 1a39 to the dial tone:

(2) +, 1UeV, 1v37, 1d38, 1k40, 1a39, WZ

The dial tone is transmitted inductively from the winding V to the windings I and II of the transformer 1Ue and sent out from the latter via the line conductors $a1$ and $b2$ to the subscriber so as to cause him to start dialing. After energization of relay 1C the energization circuit for winding III of relay 1A is interrupted. Relay 1A is however held via its winding I and II and the subscriber loop in the following circuit:

(3) +, 1AII, $b2$ -wire, subscriber loop, $a1$ -wire, 1AI, 1c6, —

Via contact 1c90, ground potential is applied to the private conductor 104c leading to the successive connecting device:

(4) +, 1c90, Gr87, 1z84, 104c conductor, . . .

Responsive to the dial tone, the subscriber now sends out by means of his dial the first series of impulses which, let us say, consists of six impulses. In the supply transmission, the impulse receiving relay 1A deenergizes in a pulse-like manner. Upon the first deenergization of the relay 1A, due to the opening of the contact 1a23, relay IV is connected via its winding I:

(5) +, . . ., $c3$ -wire, 1a22, 1VI, 1f24, Wz30, 1c31, —

By closing the contact 1a22 the seizure relay 1C is short-circuited, but is nevertheless held for a series of impulses, due to its delay in deenergizing. The seizure relay 1C, after cutting off of its energizing circuit, was held in the following circuit:

(6) +, . . ., $c3$ -wire, 1C, 1a23, 1f24, Wz30, 1c31, —

After energization of the relay V by means of its contact 1v99, the relay 1K is energized which relay is held via its contact 1k100, independently of contact 1v99 in the following circuit:

(7) +, 1c90, 1a98, 1k100, 1KII, —

Furthermore, upon energization of relay 1K the dial tone is disconnected by the opening of the contact 1k40 and preparation is made for sending out of a busy signal by the closing of the contact 1k41.

Upon the deenergization of the relay 1A, the storage magnet 1EM of the storage device is energized via contact 1a95 in the following circuit:

(8) +, 1c90, 1a95, 1pe96, 1EM, —

The storage magnet 1EM is attracted and after energization of the relay A, the EM magnet which deenergizes shifts the laminations one step further. The off-normal contacts are thereby actuated. Minus potential lies, via contact 1so75 in the following circuit on the outgoing line conductor $a102$:

(9)

—, $\frac{1UI}{Wz76}$, 1so75, 1y73, 1k71, 1c56, 1i17, 102a conductor, . . .

By the application of this voltage to the $a102$ conductor a setting set associated with the succeeding connecting device is excited. The relay 1U receives current insufficient to effect its operation while the individual set is being seized and can therefore not be attracted. At the

end of the first impulse, the pulse receiving relay 1A is again attracted and by opening its contact 1a22, again connects the seizure relay 1C (cf. circuit 6) and, via its contact 1a23, short-circuits the relay IV which, however, due to its delayed deenergization, remains energized during a series of pulses. Furthermore, by the opening of the contact 1a95, the storage magnet 1EM is disconnected, which magnet, after deenergizing, energizes the marker magnet 1MM via contact 1e93:

(10) +, 1c90, 1em93, 1v94, 1MM, —

The marker magnet 1MM holds itself energized independently of the contact 1em93 by its own contact 1mm92 which is parallel to said last mentioned contact. After the second impulse the laminations are moved forward by one step further. The second lamination is thereby pressed by the marker magnet 1MM under the aforementioned guide ring. After the sixth pulse, the relay 1A remains energized so that relay IV deenergizes with delay by the short-circuiting of its windings I by contact 1a23. After the deenergizing of relay V, the marker magnet 1MM is disconnected by the opening of the contact 1v94 so that the sixth lamination can no longer be pushed below the guide ring like the preceding five laminations. This lamination remains above the guide ring when the laminations are moved one step further forward upon the occurrence of the next train of pulses. The further trains of pulses which arrive are taken up by the storage device and stored in the same manner as already described.

As soon as one setting set seizes the succeeding connecting device, the high ohmic starting relay of said setting device which is connected to the 102a conductor is disconnected and via the low ohmic test relay which is now connected, an amplification of current is obtained so that the relay 1U in the storage device can energize via its winding I in accordance with circuit 9. Via contact 1u60 the de-storing magnet 1AM and the pulse transmitting relay 1J are energized in the following circuits:

(11) +, 1y58, 1y59, 1u60, 1i70, 1AM, —

(12) +, 1y58, 1y59, 1u60, 1i61, Gr65, Wi69, 1JII, —

The relay 1J can however not be actuated since it is counter-energized via its windings I and II by the charging current for the capacitor Ko66:

(13) +, 1y58, 1y59, 1u60, 1i61, Ko66, 1JI, 1JII, —

As soon as the capacitor Ko66 is charged, relay 1J is actuated via its winding III and holds itself, due to the discharge current Ko66 in the following circuit:

(14) +(Ko66), Gr65, Wi69, 1JII, 1JII, 1JI, —(Ko66)

Furthermore, the capacitor further discharges in the following circuit:

(15) +(Ko66, 1i62, Gr63, Wi64, 1JI, —Ko66)

During the time of actuation of the relay 1J, voltage is disconnected from the 102a conductor by the opening of the contact 1i17 (see circuit 9) and a pulse is thus transmitted to the setting set. Furthermore, by the opening of the contact 1i70, the de-storage magnet 1Am is discontinued, which magnet, after it has deenergized, prepares a test circuit for the test wiper pk55 of the storer selector by closing the contact 1am54:

(16) +, 1c90, 1i91, 1pk55, 1am54, Gr53, 1d47, 1YI, —

Since the second lamination is below the guide ring, this circuit is not closed, so that relay 1Y cannot energize. After the discharge of the capacitor Ko66, relay 1J de-energizes and by closing its contact 1i17 again applies voltage to the 102a conductor (cf. circuit 9). Via contact 1i70, the de-storage magnet 1Am is again energized and the charging circuit for the capacitor Ko66 is again closed via contact 1i61. During the time in which relay

1J was energized, relay 1U was held via its winding II in the following circuit since the holding circuit for winding I was interrupted by the opening of the contact 1i17:

(17) +, 1c90, 1i91, 1UII, —

During the sending out of the sixth pulse, the test wiper pk55 is on the lamination located above the guide ring so that the energizing circuit for the relay 1Y (see circuit 16) is closed after the deenergization of the destorage magnet 1AM. Relay 1Y actuates and holds itself, independently of its holding circuit, in the following circuit:

(18) +, 1k19, 1u48, 1y51, 1d47, 1YI, —

By opening of contact 1y58 and 1y59, ground potential is removed from the pulse transmitting relay 1J and the destorage relay 1AM so that they can no longer energize. Via contact 1y72, relay 1U is held via its winding I in the following circuit:

(19) +, . . . , 102a-wire, 1i17, 1c56, 1k71, 1y72, 1u77, 1UI, —

After the setting of the succeeding connecting device of a first group selector to an idle outgoing line, ground potential is disconnected from the 102a conductor so that relay 1U deenergizes. After the deenergization of relay 1U, the holding circuit for relay 1Y (cf. circuit 18) is interrupted by the opening of the contact 1u48, but relay 1Y is held by the discharge current until the discharge of the capacitor Ko49:

(20) +(Ko49), 1y51, 1d47, 1YI
(minus line), Wi50, —(Ko49)

Furthermore, via contact 1u78, relay 1D is connected to the 102a conductor in the following circuit:

(21) +, 1c90, Gr87, 1D, 1d30, 1u78, 1y72, 1k71, 1c56, 1i17, 102a conductor, . . .

If the group selector has been set by the train of pulses sent out to an outgoing connecting device which operates in accordance with the same technique as described (pulse-wise interruption of the voltage), no voltage is present therein on the 102a conductor; relay 1D cannot energize. If there is involved, however, a connecting device which is set by ground current pulses, this is made known by the placing of minus voltage on the 102a conductor, so that the relay 1D energizes.

By opening contact 1d38, the prepared connecting of the busy signal is interrupted. Relay 1D maintains itself independently of the energizing circuit in the following holding circuit:

(22) +, 1c90, Gr87, 1D, 1d79, 1y81, —

By opening contact 1d47, the short-circuit for the winding II of the relay 1Y is interrupted, so that the relay 1Y deenergizes after discharge of the capacitor Ko49. Furthermore, by opening contact 1a98, relay 1K is disconnected (cf. circuit 7). After the deenergization of relay 1K relay 1U is energized in the following circuit via the contacts 1k20 and 1k21 of relay 1K:

(23) +, 1k20, 1k21, 1so75, $\frac{1UI}{Wi76}$, —

Via relay 1u60, the destorage magnet 1AM (cf. current path 11) is energized, and the pulse transmitting relay 1J is connected (cf. circuits 12 to 15). As soon as the contact arm 1pk55 has reached the next marked lamination, relay 1Y energizes (cf. circuit 16) and interrupts the further transmission of pulses. Relay 1Y is held by the discharge current of the capacitor Ko49 (cf. circuit 20) and deenergizes with a very strong time delay after discharge of the capacitor Ko49 via winding 1YII. The closing of contacts 1y58 and 1y59 initiates the sending out of the next train of pulses.

During the time of energization of the pulse trans-

mitting relay 1J, a ground pulse is sent out in each case via the 102a conductor, by the application of ground:

(24) +, 1k20, 1i16, 102a-wire, . . .

After the sending out of all trains of pulses relay 1U is disconnected by the opening of the normal contact 1so75.

If the relay 1D does not operate, relay 1Y deenergizes and via its contact 1y73 connects voltage to the 102a conductor (cf. circuit 9) so as to obtain a setting set of the connecting device reached. After connection of a setting set, the storage of the trains of pulses is introduced as already described. When all digits have been removed from the storage device, the normal contact 1so75 of the pulse repeater is interrupted and thus the start circuit for further setting sets is interrupted.

If the selector arranged in the succeeding connecting device does not find any idle outgoing connecting line, then after the stopping of the selector at a full-rotation step, voltage is applied to the 103b conductor. The metering relay 1Z is thereby energized via its winding I:

(25) +, 1k19, 1k18, 1Z1, Dr12, 1UeIV, 103b-wire, . . .

By the opening of the contact 1z84, ground potential is removed from the 104c conductor (cf. circuit 4) and succeeding connecting device is thereby released. Relay 1Z holds itself, independently of its energizing circuit, via its winding II in the following circuit:

(26) +, 1c90, 1d98, 1k100, 1z101, 1ZII, —

By closing the contact 1z42, a busy signal is connected to the winding V of the transformer 1Ue:

(27) +, 1UeV, 1v37, 1d38, 1k41, 1z42, busy signal

From winding V, busy tone is transmitted to the calling subscriber via the windings I and II of the transformer 1Ue. The busy signal causes the calling subscriber to release the seized connecting device by replacing the receiver.

Furthermore, when the selector stops at the full rotation step, the holding circuit for relay 1U (cf. circuit 19) is interrupted. After release of relay 1U, the holding circuit for relay 1Y (cf. current path 18) is opened by the opening of contact 1u48, relay 1Y however holding itself until the discharge of the capacitor Ko49 in accordance with circuit 20.

As soon as the calling subscriber, as a result of the busy signal has replaced his receiver, the holding circuit for windings I and II of relay 1A (cf. circuit 3) is interrupted. Relay 1A deenergizes and via its contact 1a22 short circuits the winding of the seizure relay 1C which is thereby caused to deenergize with delay. During the restoring time of relay 1C, relay 1V can energize in accordance with circuit 5. Furthermore, the closure of contact 1a95, the storage magnet 1EM is connected in accordance with the circuit 8. As soon as relay 1V is energized and the seizure relay 1C has restored, relay 1K is held independently of the holding circuit via its winding II (cf. circuit 7) via its winding I:

(28) +, . . ., c3-wire, 1a22, 1y26, 1K, 1c32, —

After the delayed release of the seizure relay 1C, the holding circuit for relay IV is interrupted by the opening of the contact 1c31 so that relay IV deenergizes. Furthermore, by the opening of contact 1c98, relay 1Z and the storage magnet 1EM are disconnected. By the closure of contact 1c27, relay 1U is energized via its winding I in the following circuit:

(29) +, 1y58, 1c57, 1k71, 1y73, 1so75, $\frac{1UI}{Wi76}$ —

Relay 1U actuates and via its contact 1u60, closes the circuit 11 for energizing the storage magnet, 1AM and the circuits 12 and 13 for the pulse transmitting relay 1J. Relay 1J actuates, after the capacitor Ko66 has been charged and holds itself until discharge of this capacitor in accordance with circuits 14 and 15. In the meantime,

relay IV releases and by opening the contact 1v26, interrupts the holding circuit for relay 1K (cf. circuit 28). After the delayed release of relay 1K, relay 1U is held in the following circuit instead of circuit 29:

(30) +, 1k20, 1k21, 1so75, $\frac{1UI}{Wi76}$ —

Upon actuation of relay 1J, the storage magnet 1AM is disconnected by the opening of contact 1v70. As soon as relay 1J releases after the discharge of the capacitor Ko66, the charging circuit for this capacitor is again closed by the closing of contact 1i61 and the storage magnet 1AM is again connected via contact 1v70. This interplay between the pulse transmitting relay 1J and the storage magnet 1AM continues until, after reaching the normal position of the storage device, the normal contact 1so75 is opened and the holding circuit for relay 1U (cf. circuit 30) is thereby interrupted.

Relay 1U is however held during the time of energization of the storage magnet 1AM by the contact 1am74 which lies in parallel to contact 1so75. After the actuation of the pulse transmitting relay 1J, the storage magnet 1AM is disconnected by the opening of the contact 1v70, this magnet in its turn disconnecting relay 1U by the opening of contact 1am74. Relay 1U, by opening its contact 1u70, interrupts the energizing circuit for relay 1J and the storage magnet 1AM.

Furthermore, via contact 1u28, the seizure circuit for the supply transformation SpUe shown is prepared (cf. circuit 1). The supply transformation is thus again in normal condition and can again be seized.

If however no busy signal is transmitted from the succeeding connecting device, then, as already mentioned, after the storage of the last impulse by the opening of the contact 1so75, the circuit for obtaining a further setting set (cf. circuit 9) is interrupted.

If the connection is switched through to the subscriber line desired, and if the latter is idle, then during the release time of relay 1Y, voltage is applied to the 102a conductor by the succeeding connecting device so that relay 1D energizes via current path 21. Via contact 1d80, relay 1D closes a holding circuit for itself (cf. circuit 22). Via contact 1d97, ground is applied to the outgoing 104c conductor independent of circuit 4:

(31) +, 1c90, 1d97, Gr88, c104 conductor, . . .

At the same time, due to the opening of the contact 1d98, the holding circuit for relay 1K (cf. circuit 7) is interrupted, so that relay 1K restores with time delay.

As soon as the called subscriber answers, voltage is applied to the 103b conductor by the succeeding connecting device (connector). No switching operations are thereby produced in the battery feed transformation, since the energizing circuit for relay 1Z is interrupted after the restoration of relay 1K (cf. circuit 25).

After completion of the conversation, the connection is released when the calling subscriber hangs up. The pulse receiving relay 1A restores (cf. circuit 3), since after the receiver has been hung up, the subscriber's loop is opened. By closing the contact 1a22, the winding of the seizure relay 1C is short-circuited and such relay 1C is thereby caused to restore with time delay. At the same time, by the opening of the contact 1a23, relay IV (cf. circuit 5) is connected. Furthermore, via contact 1a95, the circuit for energizing the storage magnet 1EM (cf. circuit 8) is closed. After actuation of relay IV, relay 1D is held, independently of circuit 22 in the following circuit:

(32) +, 1v85, 1D, 1d79, Wi82, —

Furthermore, ground is applied to the outgoing 104c conductor independently of circuit 31 (via contact 1v86).

(33) +, 1v86, 104c conductor, . . .

After the delayed release of the seizure relay 1C, the

circuit for the storage magnet 1EM is interrupted by the opening of the contact 1c90 so that the storage magnet restores. At the same time the holding circuit for relay 1D (cf. circuit 22) is interrupted, but relay 1D continues to hold itself in accordance with the circuit 32. Furthermore, after the opening of contact 1c90, ground potential would be removed from the 104c conductor if it were not connected in accordance with circuit 33 via contact 1v86 in order not to release the connection which has been made until the metering pulse has been transmitted. After the closing of contact 1c32, relay 1K can energize via its winding I in the circuit 28. Furthermore, a circuit for winding I of the metering relay 1Z is closed via contact 1c46:

(34) +, 1c46, 1ZI, Dr12, 1UIV, b103 conductor, . . .

Finally, after the release of relay 1C, the holding circuit for relay IV (cf. circuit 5) is interrupted, by the opening of the contact 1c31, so that relay IV restores with time delay. After energization of relay 1K, relay 1U is connected in accordance with circuit 29 by the closing of contact 1k71, Relay 1Z by closing its contact 1z36, applies voltage to the z5 conductor:

(35) -, 1z36, 1d35, z5 conductor, . . .

After the energization of relay 1U the detorage magnet 1AM and the pulse transmitting relay 1J are connected via contact 1u60. There now take place exactly the same switching operations as already described in connection with the release after transmission of busy signal. After the delayed release of relay IV, the holding circuit for relay 1D (cf. circuit 35) is interrupted. At the same time, by the opening of contact 1v86, ground is removed from the outgoing 104c conductor. The succeeding connecting devices are in this manner released. As a result of the release of the succeeding connecting device, the voltage lying on the 103b conductor is disconnected and the metering relay 1Z releases (cf. circuit 34). It may be mentioned here that the relay 1D after energization of the metering relay 1Z was held, via contact 1z83, so that relay 1D after the release of relay 1Z also releases. By the opening of contact 1z36, the transmission of the metering impulse is terminated. As soon as relay 1D is released, relay 1K is caused to release by the opening of contact 1d25 over which, after the opening of contact 1v26, the holding circuit for winding I of relay 1K was maintained (cf. circuit 28). After relay 1K has restored, the seizure circuit (cf. circuit 1) is again prepared via contact 1k29 and the supply transformation can again be seized.

It may also be mentioned here that in case of long-distance calls, the long-distance marking relay 1F is caused to energize via its winding II over the 105d conductor. Independently of this energizing circuit, it holds itself by connecting its winding I after the opening of contact 1f24 over the incoming c3 conductor. By closing contact 1f33, the calling subscriber line is marked as being busy with a long-distance call by direct application of ground potential to the d4 conductor. Furthermore, a circuit for the metering relay 1Z is closed via contact 1f45. The metering current pulses are transmitted during the conversation by the application of voltage to the 103b conductor, so that relay 1Z can energize and transfer these metering pulses in circuit 35 to the charge meter of the calling subscriber. The release at the end of the conversation is the same as already described in connection with a connection to a subscriber of the same local network.

FIGS. 2a and 2b show the feed transmission 3SpUe for the called subscriber as well as the relay set associated with this feed transmission. This relay set tests the called line for busy or idle condition. Switching means are associated with the feed transmission for controlling the ringing of the called party and likewise the transmission of ringing tone and busy tone to the calling party.

75

FIGS. 3a and 3b show the connector LW and the setting set 4ES allocated to the connector.

Voltage is placed on the conductor a120 (see circuit 9) as soon as a preceding group selector has established connection with the feed transmission 3SpUe.

10 If the feed transmission is connected with a succeeding group selector over which the connector is to be reached, the start relay of the setting set allotted to such group selector will be energized. When such group selector is set, the line conductors and the control or private conductors are directly switched through and it may therefore be assumed in the following explanations, that the feed transmission 3SpUe is directly connected with the connector LW.

15 Responsive to placing voltage on the conductor a120 in the feed transmission 3SpUe, the start relay 4An in the setting set 4ES will energize by way of its windings I and II:

(36) +, 4a36, 4e35, 4ANII, 4e32, 4ANI, 4d31, 4u30, conductor an20, Gr5, 4cg4, conductor a200 (FIG. 3), 3UeIII, 3c6, 3UeI, conductor a120, . . ., -

20 It may be mentioned at this point that the supervising relay 4U is in the normal condition of the setting set energized:

(37) +, 4d71, 4e72, 4h73, $\frac{4U}{Ko74, Wi75}$, -

25 The capacitor Ko74 is so dimensioned that the supervising relay 4U does not release during the interruptions of the circuit 37 incident to the setting and seizure of the setting set. It releases only when the current is interrupted for an extended interval, for example, responsive to the blowing of a fuse. In such case, the start circuit is interrupted by the opening of contact 4u30, and the setting set cannot be seized.

30 As soon as the start relay 4AN is energized, relay 4E will be connected by way of contact 4an64. Relay 4E is upon energization held over its winding I while winding II is short circuited by way of contact 4e63:

(38) +, 4an64, 4e63, 4EI, -

35 Closure of contact 4e33 and opening of contact 4e32 effects connection of the resistor Wi34 in the circuit 36 in place of the winding II of the start relay 4AN. Relay 4V is energized over its windings I and II, by way of contact 4e82, holding itself over its winding II while its winding I is short circuited by way of contact 4v84:

40 (39) +, 4e82, 4v84, 4VII, -

45 Closure of contact 4e81 finally starts the operation of the motor switch in the setting set by energization of the field coils 4Na and 4Nb. These field coils 4Na and 4Nb are displaced by 90°. An armature is rotatably 50 journaled at the point of axial intersection of the field coils, such armature being rotated by the action of the magnetic fields alternately produced by the field coils. The rotary motion of the armature is transmitted by a gear to the switch shaft and therewith to the wipers 4n21 and 4n27 carried thereby. The field coils are alternately operatively connected by cam contacts 4na76 and 4nb77 which are controlled by the switch shaft.

55 When both field coils are energized, the armature will be held against rotation and the switch operation is thus stopped. In the illustrated position of the contacts, the field coil 4Nb is energized:

(40) +, 4e81, 4nb77, 4Nb, -

60 The field coil 4Nb attracts the armature, thereby causing closure of the cam contact 4na76 and opening of the cam contact 4nb77, and thus operatively connecting the field coil 4Na:

(41) +, 4e81, 4na76, 4Na, -

65 The armature is now attracted by the field coil 4Na.

11

The cam contact 4na76 is now opened again and the field coil 4Nb is energized by way of the cam contact 4nb77. The wipers 4n21 to 4n27 are at the same time moved.

As soon as the wiper 4n21 reaches the bank contact to which is connected the connector, the testing relay 4P can energize in the following circuit by way of voltage lying on the conductor a120:

(42)

+, 4PII, 4PI, 4v38, 4u37, wiper 4n21, 4cg4, conductor a200, (FIG. 3) UeIII, 3c6, 3UeI, conductor a120, 721, —

The current flowing over the conductor a120 is increased by the switching in of the low resistance windings of the testing relay 4P. This criterion is evaluated in the storer (FIG. 1) and the digit required for the setting of the connector to the desired decade is transmitted from the storer.

Closure of contact 4p78 effects energization of both field coils of the motor switch and the operation of the switch is in this manner stopped. Relay 4A is now operatively connected over its winding II by way of contact 4p44:

(43)

+, 4p44, 44d41, 4AI, —

Relay 4A short circuits the winding II of the testing relay 4P by way of contact 4a45. Moreover, opening contact 4a36 interrupts the holding circuit for the start relay 4AN (see circuit 36). Due to opening of contact 4a106 and closure of contact 4a57, the seizure relay 4C can now energize:

(44)

+, 4a57, Wi105, 4C, 4v108, —

The switch is held with the wipers on the corresponding bank contacts independently of the testing relay due to closure of contact 4c79 in parallel with contact 4p78 of the testing relay.

After release of the start relay 4AN contact 4an64 disconnects relay 4E which releases with delay owing to the short circuit of its winding II, and opening of contact 4e81 disconnects the energizing circuit of the field coils 4Na and 4Nb. Opening of contact 4e82 disconnects relay 4V which releases with delay due to the short circuit of its winding I.

The current impulses transmitted from the storer (FIG. 1) arrive by way of the conductor a120 as current interruptions during the release time of the relays 4E and 4V, respectively. Relay 4P releases impulsewise and causes by the opening of contact 4p44 impulsewise release of relay 4A (see circuit 43). Upon each release of relay 4A, relay 4C is short circuited over contact 4a106, relay 4C accordingly remaining energized (see circuit 44) during the transmission of an impulse series despite the impulsewise opening of contact 4a57. By way of contact 4a56, relay 4V which is held actuated, is energized again incident to each impulse interruption:

(45)

+, 4a56, 4c55, 4v54, 4e83, 4v84, 4VII, —

Upon occurrence of the first current interruption of an impulse series consisting of three impulses, relay 4R is energized by way of contact 4a56:

(46)

+, 4a56, 4c55, 4v54, 4h86, 4s90, 4RI, —

Relay 4R belongs to the relay counting chain comprising the relays 4R, 4S, 4T, 4W and the auxiliary relay 4H, serving for the marking of the desired decade. When relay 4A energizes again at the conclusion of the impulse, relay 4C is according to circuit 44 switched in and relay 4R is held over its winding II:

(47)

+, 4a57, 4r96, 4RII, —

12

Relay 4S is now connected by way of its winding II, by the actuation of contact 4r99:

(48) +, 4a47, 4r99, 4h101, 4SII, —

5 Upon receipt of the second current impulse relay 4S is held during the release of relay 4A by way of contact 4a56, over its winding I:

(49) +, 4a56, 4c55, 4v54, 4s91, 4SI, —

10 The energizing circuit for relay 4R (see circuit 46) is interrupted by the opening of contact 4s90 and relay 4R consequently releases. When relay 4A energizes again at the conclusion of the current impulse, relay 4S will be held over its winding II in the circuit:

15 (50) +, 4a57, 4r97, 4s98, 4SII, —

Relay 4H is now operatively connected by way of contact 4s103 over its winding II:

20 (51) +, 4a57, 4r100, 4s103, 4HII, —

Upon arrival of the third current impulse, relay 4S will be held according to circuit 49, and relay 4H is held in the circuit:

25 (52) +, 4a56, 4c55, 4v54, 4h85, 4u87, 4HI, —

Relay 4R is connected over its winding I by way of contact 4h85:

30 (53) +, 4a56, 4c55, 4v54, 4h85, 4r88, 4s89, 4RI, —

When relay 4A energizes again at the conclusion of the current impulse, relay 4R will be held in the circuit 47; relay 4H, winding II, is held in the circuit:

35 (54) +, 4a57, 4r99, 4h102, 4TI, 4HII, —

Relay 4T energizes in this circuit. The holding circuit for the winding I of relay 4S is interrupted and this relay restores. Accordingly, at the conclusion of the third current impulse, relays 4R, 4T and the auxiliary relay 4H of the relay counting chain are energized.

After the last current impulse, the holding circuit for relay 4V (see circuit 45) is not closed and relay 4V accordingly releases with a delay. Relay 4V, by opening its contact 4v38 disconnects the testing relay 4P (see circuit 47). Relay 4A is held over its winding I and conductor a120 (see circuit 19) by way of contact 4v39:

(55) +, 4a43, 4AI, 4v39, 4u37, wiper 4n21, 4cg4, conductor a200, 3UeIII, 3c6, 3UeI, conductor a120, . . . , —

Upon release of relay 4P, the winding II of relay 4A (see circuit 43) is disconnected.

After the delayed release of relay 4V, a circuit is closed for relay 4Ua by way of contact 4v49 (FIG. 4). In this circuit, relay 3U arranged in the feed transmission 3SpUe (FIG. 3) energizes:

(56) +, . . . , conductor c122, 3c85, 3c90, EUIII, 3u92, conductor d203, 4cg6, 4u23-wiper, 4v49, 4a50, Wi51, 4UaI, —

Relay 4Ua, by closing its contact 4ua109, closes a holding circuit over its winding II which is independent of its energizing circuit. In this circuit, the seizure relay 4C is held which would deenergize after release of relay 4V and opening of contact 4v108:

(57) +, 4a57, Wi105, 4C, 4UaII, 4ua109, —

Relay 4D is operatively connected by way of contact 4ua65:

(58) +, 4t69, 4D, 4ua65, —

Relay 4D energizes and over its contact 4d62 connects the field coils 4Ma and 4Mb of the motor of the connector.

75 The operation of this motor switch is the same as already

explained in connection with the connecting switch for the setting set. In the illustrated normal position, field coil 4Ma will be energized:

(59) +, 4d62, 4n26-wiper, 4ma8, 4Ma, —

The armature of the motor switch is attracted by the field coil 4Ma. The cam contact 4ma8 is now opened and the cam contact 4mb9 is closed, resulting in energization of field coil 4Mb:

(60) +, 4d62, 4n26-wiper, 4mb9, 4Mb, —

The testing relay 4P is simultaneously with the switching in of the field coils connected to the test wiper 4d13, over contact 4d42:

(61) +, 4PII, 4PI, 4d42, 4u22-wiper, d413-wiper, . . .

It may be mentioned at this point that voltage is connected to a main stop contact arranged ahead of the third decade, in the circuit:

(62) —, Wi110, 4s122, 4t129, 4r125, 4w124, 4ub135, HR3, . . .

As soon as the test wiper d413 reaches this marked main stop contact, test relay 4P will energize in accordance with circuit 61. Closure of its contact 4p60 will stop the operation of the switch due to simultaneous energization of its field coils 4Ma and 4Mb. The two field coils are then interconnected in the circuit:

(63) 4Ma, 4n25-wiper, 4p60, 4n27-wiper, 4Mb

Closure of contact 4p44 short circuits the winding I of relay 4A causing deenergization thereof. After release of relay 4A, instead of ground according to circuit 55, there will be ground on the conductor a120 of the feed transmission 3SpUe in FIG. 3, in the circuit:

(64) +, 4p44, 4d40, 4p39, 4u37, 4n21-wiper, 4cg4, a200-wiper, 3UIII, 3c6, 3UeI, a120-wiper, . . ., —

By the closure of contact 4a61 parallel to contact 4p60, both field coils 4Ma and 4Mb (see circuit 63), will be interconnected independently of the release of test relay 4P and will accordingly be simultaneously energized. The holding circuits for relays S, T and H of the relay counting chain (see circuits 47 and 54) will be interrupted by the opening of contact 4a57. The opening of this contact also interrupts the holding circuit for relay 4C and for winding II of relay 4Ua (see circuit 57). With the exception of relay 4C the winding of which is short circuited over contact 4a106, the relays restore without delay. After the release of the relays of the counting chain and the relay 4Ua, the energizing circuit for the test relay 4P (see circuits 61 and 62) is interrupted and relay 4P releases. Opening of contact 4t69 disconnects relay 4D (see circuit 58) and this relay restores with delay due to its slow-to-release feature.

Relay 4P by opening its contact 4p44 interrupts circuit 64, thereby giving to the storer a signal that the switch has been set. Upon opening contact 4p60, the field coils 4Ma and 4Mb of the connector are as already mentioned energized over contact 4a61 and the switch is thus held with its wipers set on the desired bank contacts. After the delayed release of relay 4D, the two field coils of the connector are disconnected by the opening of contact 4d62 and such coils are, accordingly, deenergized. Closure of contact 4d31 extends the start conductor an20 through to the start relay 4AN (see circuit 36). After release of the relay 4D, the setting set is again in normal position and ready for use in connection with another call.

In the feed transmission, the following switching oper-

ations will take place after the energization of relay 3U (see circuit 56). An energizing circuit is closed by way of contact 3u16 for the toll marking relay 3F:

5 (65) +, 3u16, 3c17, 3FI, 3z22, 3g20, Dr2, 3UeII, conductor b121, . . .

In incoming toll calls, during the transmission of the last current impulse series which serves for the setting to the desired subscriber station, voltage is placed in the toll transmission circuit on the conductor b121 and the toll marking relay can accordingly energize in the circuit 65.

Independently of its energizing circuit, relay 3U after closure of its contact 3u91 will hold itself over its winding III in the circuit:

15 (66) +, . . . conductor c122, 3c85, 3c90, 3UIII, 3u91, Wi93, —

The energizing circuit for relay 3U (see circuit 56) is at the same time interrupted by the opening of contact 3u92.

20 The setting set 4ES (FIG. 4) is again placed in operation for the transmission of the last current impulse series which serves to set the connector with its wipers in engagement with the bank contacts of the desired subscriber line. The switching operations for placing the setting set in operation, up to the transmission of the last current impulse correspond to those already described (see circuits 35 to 54).

25 It shall be assumed that the last impulse series consists again of three current impulses. The relay chain is accordingly switched as already described in connection with the switching operations incident to the receipt of the penultimate impulse series (see circuits 46 to 54). At the conclusion of the impulse series, that is, after the third impulse, relays 4R, 4H and 4T will be energized (see circuits 47 and 48).

30 Responsive to delayed release of relay 4V, upon conclusion of the impulse series, the test relay 4P is disconnected by opening of contact 4v38 and relay 4A is operatively connected by closure of contact 4v39 (see circuits 42 and 55). Relay 4Ua is connected to the conductor d203 by way of contact 4v49. However, relay 4Ua cannot energize, since relay 3U is in the feed transmission energized and ground is accordingly disconnected from the conductor d203 due to opening of contact 3u92 (see circuit 56).

35 Relay 4C is disconnected by the opening of contact 4v108 (see circuit 44) and restores since the circuit 57 is not closed by way of contact 4ua109. Responsive to release of the test relay 4P, winding II of relay 4A is disconnected but relay 4A as already mentioned remains actuated over its winding I in the circuit 55. As soon as relay 4C restores, relay 4Ub is connected over its winding II:

40 (67) +, 4a57, 4UbII, 4c104, 4v107, —

45 The third step of each decade is marked by connecting voltage thereto over contact 4ub135 and the contact pyramid of the counting relay chain:

50 (68) —, Wi110, 4s122, 4t129, 4r125, 4w124, 4ub135, step 3 of each decade.

55 Relay 4D is switched in over contacts 4ub66 and 4t69:

(69) +, 4t69, 4D, Gr130, 4ub66, —

60 Relay 4D closes over contact 4d70 a holding circuit for relay 4Ub by way of its winding I:

(70) +, 4d70, 4UbI, 4ub66, —

65 The field coils 4Ma and 4Mb of the connector are connected for operation upon closure of contact 4d62 (see circuits 59 and 60). As already explained, alternate energization of the two field coils will impart rotation to the

switch wipers. As soon as the test wiper $d413$ has reached the third step in the third decade, the test relay $4P$ will energize in accordance with circuits **61** and **68**. The circuit **61** was closed upon energization of relay $4D$ by way of its contact $4d42$. Upon energization of test relay $4P$ the field coils $4Ma$ and $4Mb$ are simultaneously energized by way of contact $4p60$ (see circuit **63**). The operation of the switch is stopped and the wipers thereof remain on the step reached. Responsive to energization of test relay $4P$, the winding I of relay $4A$ is short circuited by way of contacts $4p44$ and $4d49$, causing relay $4A$ to release with some delay.

Responsive to delayed release of relay $4A$, ground is placed by contact $4a56$ on the conductor $d203$, thereby closing a circuit for the energization of the seizure relay **3C** in the feed transmission $3SpUe$:

(71) +, $4a56$, $4v53$, $4ub52$, $4d47$, $4n23$ -wiper,
 $4cg6$, conductor $d203$, $3u82$, $3c84$, $3CII$, —

Relay **3C** is held over the conductor $c122$ independently of its energizing circuit:

(72) +, . . . , conductor $c122$, $3CII$, $3c83$, $3CII$, —

The energizing circuit **71** is at the same time interrupted by the opening of contact $3c84$.

In the setting set of the connector, the holding circuit for the relays of the counting chain had been interrupted upon release of relay $4A$ due to opening of contact $4a57$, and relays $4R$, $4H$ and $4T$ are accordingly restored. Opening of contacts $4t129$ and $4r125$ interrupts the circuit **68**, causing release of relay $4P$. Opening of contact $4r69$ interrupts the holding circuit **69** for relay $4D$ and this relay releases with some delay. Relay $4P$ upon releasing disconnects ground from the conductor $a200$ by opening its contact $4p44$. Relay $4D$, upon releasing with delay, opens its contact $4d62$, thereby disconnecting the energizing circuit for the two field coils $4Ma$ and $4Mb$ of the conductor. Opening of contact $4d70$ interrupts the holding circuit **70** for relay $4Ub$ which restores with delay. During the release interval of relay $4Ub$, a circuit is closed for the energization of the seizure relay $4Cg$ of the connector:

(73) +, $4a56$, $4v53$, $4ub52$, $4d48$, $4n24$ -wiper, $4CgII$, —

The setting set is responsive to delay release of relay $5Ub$ again at normal and ready for use in the extension of another call.

In the connector, the conductor $d203$ had been connected with the test wiper $c412$ upon energization of the seizure relay $4Cg$. The winding I of the seizure relay $4Cg$ and the winding of the line wiper control magnet $4Ad$ are now connected with the conductor $c202$ by way of contact $4cg1$. Opening of contact $4cg4$ interrupts the start circuit **36**.

In the feed transmission, the energizing circuit for the toll identifying relay (see circuit **65**) had been interrupted by the opening of contact $3c17$ responsive to energization of the seizure relay **3C**. Upon closure of contact $3c5$, voltage will be on the conductor $a120$ by way of winding I of relay **3E**, and relay **1D** (see circuit **21**) accordingly energizes in the feed transmission $SpUe$ (FIG. 1) of the calling subscriber:

(74) —, $3z29$, $3E1$, $3c5$, $3UeI$,
conductor $a120$, . . . , $1D$, —

Relay **3E** receives in this circuit insufficient current and cannot energize. The seizure relay $4Cg$ of the connector is held over its winding I by way of contact $3c52$, independently of its energizing circuit **73**:

(75) +, $3c52$, $W197$, conductor $c202$, $4cg1$, $4CgI$, $4Ad$, —

The line wiper control magnet $4Ad$ receives in this circuit insufficient current and therefore cannot energize. Relay **3T** is switched in over its winding III by way of contact $3c52$:

(76) +, $3c52$, $3u65$, $3g62$, $3TIII$, —

The holding circuit **66** for relay **3U** is interrupted by the opening of contact $3c90$. Relay **3U** is after energization of relay **3T** and prior to completing its delayed release, again energized over its winding I :

(77) +, $3u16$, $3c18$, $3UI$, $3t13$, —

Responsive to energization of relay **3T**, relay **3G** is switched in over its winding I :

(78) +, $3c52$, $3u66$, $3t69$, $3GI$, —

Relay **3G**, by opening its contact $3g62$, interrupts the holding circuit **76** for relay **3T** and the latter deenergizes with delay. Actuation of contact $3g77$ completes a circuit for the test relay **3P**:

(79) +, $3u16$, $3c18$, $3g77$, $3PII$, $3t81$, $3PI$,
conductor $d203$, $4cg7$, $c412$ -wiper, . . . ,
(line circuit of the called subscriber)

If the line of the called subscriber is idle, test relay **3P** will energize in circuit **79** during the release interval of relay **3T** and, by closing its contact $3p38$, reconnects relay **3T** in series with relay **4R**:

(80)

25 +, $3c52$, $3TII$, $HL42$, $3t41$, $3p38$, $3RI$, $3z36$, $3a33$, —

The thermistor $HL42$ which is in parallel to the winding I of relay **3T** has normally a high resistance and the low resistance winding II of relay **3T** will accordingly receive insufficient current. When the thermistor $HL42$ is traversed by current, its resistance will steadily decrease until the energization of windings I and II is equalized when relay **3T** is caused to release by opposed energization. It may be mentioned at this point that windings I and II are connected in opposing sense. The time constant of the thermistor limits the duration of the first ring.

The resistor $W197$ included in the circuit **75** is after closure of contact $3p95$ short circuited over such contact and contact $3a96$, thereby causing energization of the line wiper control magnet $4Ad$ of the connector. The line loop in the energization circuit for relay **3A** is prepared by way of contacts $3p7$ and $3p12$:

(81) +, $3p12$, $3a10$, conductor $b201$,
 $b411$ -wiper, subscribers' line loop,
 $a410$ -wiper, conductor $a200$, $3AI$, $3p7$, $3r8$, —

Relay **3U** and test relay **3P** are after closure of contact $3p54$ held in the circuit:

50 (82) +, $3c52$, $3z53$, $3UIII$, $3PIII$, $3p54$, —

Responsive to energization of the ring control relay **3R** in circuit **80**, voltage is disconnected from the $a200$ -conductor by the opening of contact $3r8$ and alternating ringing current RW is instead connected by way of contact $3r9$ for the ringing on the called line. During the energization of relay **3R**, ringing tone **FZ** is by way of contact $4r48$ connected to the winding V of the transformer $3Ue$:

60 (83) +, $3UeV$, $3p47$, $3r48$, FZ

The ringing tone is inductively transmitted from the winding $3UeV$ to the windings I and II and from there over the conductors $a120$ and $b121$ to the calling subscriber. The circuit for relay **3R** is interrupted and the first ring concluded after release of relay **3T** and consequent opening of contact $3t41$. Relay **3R** is by way of contact $3t40$ connected to a ten-second ringing interrupter $4Sch$ and thus periodically energized in 10 second intervals, so as to ring the called line:

70 (84) —, $3a33$, $3z36$, $3RI$, $3p38$, $3t40$,
ringing interrupter $4Sch$

Closure of contact $3t56$ completes a holding circuit for relay **3P** independently of circuit **82**:

75 (85) +, $3c52$, $3t56$, $3ZI$, $3PIII$, $3p54$, —

Relay 3Z cannot energize in this circuit since it receives insufficient current by way of the low resistance winding II of relay 3U which is in accordance with circuit 82 connected in parallel to the high resistance winding of relay 3Z. Ground potential is by way of contact 3z80 directly connected to the conductor d203 thus making the called subscribers' line busy:

(86) +, 3p79, 3z80, 3a88, conductor d203, 4cg7, c412-wiper, . . . , called subscribers' line circuit

As soon as the called subscriber answers by removing his receiver, the line loop (see circuit 81) is closed and relay 3A energizes. Opening of contact 3a10 connects winding II of relay 3A in the circuit 81. The conductor b201 is over contact 3a11 connected with the winding IV of the transformer 3Ue and the line conductors are thus connected through by way of the transformer. Opening of contact 3a33 interrupts the energization circuit 84 for relay 3R preventing further energization thereof. Opening of contact 3a88 connects the winding II of relay 3Z in the circuit 86 and relay 3Z energizes. Opening of contact 3a96 connects the parallel disposed resistors W197 and W198 in the holding circuit 75 for relay 4Cg and the line wiper control magnet 4Ad so as to save current. Opening of contact 3z53 disconnects the winding II of relay 3U in the circuit 82, causing relay 3U to restore.

Relay 3Z is now held over its winding I (see circuit 85) independently of its energizing circuit. Upon delayed release of 3U, relay 3G is disconnected by the opening of contact 3u66 (see circuit 78). Upon release, relay 3G connects over its contact 3g20 voltage to the conductor b121:

(87) -, 3f24, 3z23, 3g20, Dr2, 3UeII, conductor b121, . . .

The feed transmission is after release of relay 3G in condition to permit the two subscribers to converse with each other.

Assuming that the called subscriber is the first to restore his receiver at the completion of the conversation, whereupon the calling subscriber hangs up, ground will be disconnected from the conductor c122, interrupting the holding circuit for relay 3C (see circuit 72) and thus causing relay 3C to release. Relay 3C by opening its contact 3c52 interrupts the holding circuits for relays 3P and 3Z (see circuit 85) and for the seizure relay 4cg as well as for the line wiper control magnet 4Ad in the connector (see circuit 75). Relay 3Z is still being held over its winding II and conductor d203 until the corresponding circuit is interrupted at contact 3p79 responsive to restoration of relay 3P (see circuit 86). Upon release of relay 3Z, the feed transmission 3SpUe will be at normal and in readiness for further seizure by a preceding connection device.

However, if the calling subscriber should be the first to restore his receiver, seizure relay 3C will be caused to restore due to disconnection of ground from the conductor c122. Upon opening contact 3c52, the test relay 3P and relay 3Z will be held operated in the circuit:

(88) +, 3a57, 5z58, 3z56, 3ZI, 3PIII, 3p54, -

The seizure relay 4Cg of the connector is after opening of contact 3c52 held operated by way of contacts 3a57, 5z58 and conductor c202 (see circuit 75).

When the line loop (see circuit 81) is interrupted responsive to restoration of the receiver by the called subscriber, battery feed relay 3A will deenergize and will interrupt the holding circuits for relays 3P, 3Z and for the seizure relay 3Cg of the connector, by opening its contact 3a57. Upon restoration of these relays, the feed transmission 3SpUe and the connector 4LW will again be at rest and ready for seizure by a preceding connection device.

In the event that the called subscriber is busy, the test relay 3P cannot energize in circuit 79 within the release

interval of relay 3T. After restoration of relay 3T, relay 3U will be disconnected by the opening of contact 3z13 (see circuit 77). Owing to its slow-to-release feature, relay 3U releases with delay and by opening its contact 3u66 interrupts the holding circuit for relay 3G (see circuit 78). However, relay 3G is being held operated over its winding I in the circuit:

(89) +, 3c52, 3z53, Gr68, 3g72, 3f70, 3GI, -

10 Since relay 3P is not energized, busy tone is over its contact 3p46 connected to the winding CUeV of the transformer:

(90) +, 3UeV, 3p46, 3r44, 3g43, BZ

15 The busy tone is inductively transmitted from the winding of the transformer 3UeV to the windings I and II and from there to the calling subscriber. When the calling subscriber thereupon replaces the receiver, ground potential is disconnected from the conductor c122 and the seizure relay 3C releases, since its holding circuit 72 is interrupted. Opening of contact 3c52 interrupts the holding circuit for relay 3G (see circuit 78), and relay 3G restores. Upon restoration of relay 3G, the busy tone is disconnected due to opening of contact 3g43 (see circuit 90). The feed transmission is after release of relay 3G at normal and in readiness for seizure in the extension of another call.

20 Changes may be made within the scope and spirit of the appended claims which define what is believed to be new and desired to have protected by Letters Patent.

25 I claim:

1. A circuit arrangement for use in a telephone system and the like, for testing a called subscriber's line in the extension of a connection thereto by a connector and for connecting battery feed thereto, comprising a battery feed transmission device disposed ahead of the connector and containing switching means for the testing of a called subscriber's line and for connecting battery feed thereto, a seizure relay operatively associated with said feed transmission device, circuit means effective responsive to the setting of the wipers of said connector to a predetermined bank contact group by a first impulse series for preparing an energizing circuit for said seizure relay, and means for operatively closing said energizing circuit responsive to the setting of the wipers of said connector relative to the bank contacts of a predetermined subscriber line determined by a second impulse series.

2. A circuit arrangement according to claim 1, comprising a setting set common to a plurality of connectors and containing a slow-to-release relay which is energized 50 during the receipt of the impulse series denoting the tens digit, a switch-over relay disposed in said feed transmission device, said slow-to-release relay being effective upon the release thereof at the conclusion of said impulse series to close an actuating circuit for said switch-over relay, 55 said switch-over relay completing a holding circuit for itself and simultaneously interrupting its energizing circuit.

3. A switching arrangement according to claim 1, comprising a slow-to-release relay for limiting the testing time 60 interval, a testing relay, a control relay, means controlled by said seizure relay for operatively connecting said slow-to-release relay, and means governed by said slow-to-release relay for causing energization of said control relay for operatively connecting said testing relay.

4. A circuit arrangement according to claim 3, comprising means governed by said control relay for closing the energizing circuit for said testing relay and for interrupting the circuit for said slow-to-release relay to cause operative actuation of said testing relay during the 70 release interval of said slow-to-release relay in the event test of such subscriber line shows it to be idle.

5. A circuit arrangement according to claim 4, where-in said testing relay is operative to effect transmission of busy tone to the calling subscriber in the event test 75 of such called subscriber line shows it to be busy.

6. A circuit arrangement according to claim 4, comprising a ringing relay, and circuit means effective upon energization of said testing relay for causing operative actuation of said slow-to-release relay in series with said ringing relay.

7. A circuit arrangement according to claim 6, wherein said slow-to-release relay has two oppositely effective windings, means controlled by said testing relay for operatively connecting said windings, a thermistor the resist-

ance of which increases after operative connection thereof for short circuiting one of said windings for the purpose of causing restoration of said slow-to-release relay responsive to equal energization of the two windings thereof.
